Primary Examiner — Paula Allen Greene(74) *Attorney, Agent, or Firm* — Alonzo & Associates;
Arlyn Alonzo(57) **CLAIM**

The ornamental design for a flip cover, as shown and described.

DESCRIPTION

FIG. 1 is a front view of an exemplary flip cover.

FIG. 2 is a back view thereof.

FIG. 3 is a left side view thereof.

FIG. 4 is a right side view thereof.

FIG. 5 is a bottom view thereof.

FIG. 6 is a top view thereof;

FIG. 7 is a perspective front view thereof;

FIG. 8 is a perspective back view thereof; and,

FIG. 9 is a perspective view of the flip cover in a propped up position configured to support a device (not shown).

The flip cover may be used as a covering or as a support for a device.
